His Attorneys.

UNITED STATES PATENT OFFICE.

PHILIP A. STEPHENS, OF ST. LOUIS, MISSOURI.

FIRE ESCAPE.

Application filed August 4, 1921. Serial No. 483,709.

To all whom it may concern:

Be it known that I, PHILIP A. STEPHENS, a citizen of the United States, residing at St. Louis, Missouri, have invented a new 5 and useful Improvement in Fire Escapes, of which the following is a specification.

This invention relates to fire escapes.

An object of the invention is to provide a novel and improved fire escape and fire 10 fighting equipment including a movable support arranged to operate within a guide or track supported near the cornice of a building.

Another object of the invention is to provide improved means for raising a hose by use of the invention, so that water may be discharged with greater advantage than is possible where ladders and the like are employed to raise the hose.

20 In the drawings,

Fig. 1 is a view showing the arrangement of the invention in connection with a building.

Fig. 2 is an enlarged detailed view.

25 As shown, my invention comprises a supporting track 1 which is tubular in form and which is supported at the sides of the building by brackets 2. The track 1 is open along its under side and has inwardly 30 turned edges 3. Channels or grooves are formed between the inwardly turned edges 3 and the wall of the tubular track member, which receive the wheels 4 on the movably supported truck. A large wheel or pulley 35 5 is revoluble on the axle 6 of the truck independently of the wheels 4.

As shown, the track 1 extends along the sides of the building and turns the corners of the building, so that there is a continuous 40 track around the building. This permits the movable support to operate on the track entirely around the building in either direction.

A rope 7 passes over the wheel or pulley 45 5 and is of sufficient length to permit both ends to reach the ground. From one end of the rope 7 two diverging ropes extend and carry between them a support or seating portion 8 to support a fireman or other person. Preferably, a loop 9 is secured to the rope above the seat 8 and is arranged to engage 50 the seat from falling.

A bracket 10 is connected to the rope above the seat 8 and is arranged to engage 55 and support the hose 11 and to carry the hose to the proper place for use.

When the device is not in use, the ends of the rope may be engaged within a box or case 12 at the ground or street level. This will prevent the device from being moved 60 out of place when not in use.

When the device is used for fire fighting purposes, the fireman upon the seat 8 and within the loop 9 holds the hose in proper connection with the bracket 10. The fireman may raise himself to the proper height or this may be done by others on the ground engaging the opposite end of the rope. Also, the persons on the ground may move the person in the seat 8 to positions of vantage 70 by pulling the free end of the rope in the proper direction.

I claim:

1. A device of the character described, comprising a tube supported near the top of 75 a building and having an opening through the under side thereof throughout its length, an inwardly turned flange along each side of the opening, said flanges forming channels or grooves between their inner 80 sides and the adjacent wall of the tube, a single wheel arranged to operate in each of said channels or grooves, an axle connecting said two wheels, a relatively large wheel on said axle extending through the opening in 85 the bottom of the tube between said inwardly turned flanges, a rope extending over said large wheel of sufficient length to have both ends extend to the ground, a seat support in connection with one end of the rope, and 90 a seat supported by said support.

2. A device of the character described, comprising a tube supported near the top of 95 a building and having an opening through the under side thereof throughout its length, an inwardly turned flange along each side of the openings, said flanges forming channels or grooves between their inner sides and the adjacent wall of the tube, a single wheel arranged to operate in each of 100 said channels or grooves, an axle connecting said two wheels, a relatively large wheel on said axle extending through the opening in the bottom of the tube between said inwardly turned flanges, a rope extending over said 105 large wheel of sufficient length to have both ends extend to the ground, a seat support in connection with one end of the rope, a seat support by said support, and a loop in connection with said seat support above the 110 seat.

3. A device of the character described,

comprising a tube supported near the top of a building and having an opening through the under side thereof throughout its length, an inwardly turned flange along each side of the opening, said flanges forming channels or grooves between their inner sides and the adjacent wall of the tube, a single wheel arranged to operate in each of said channels or grooves, an axle connecting said two wheels, a relatively large wheel 10 on said axle extending through the opening

in the bottom of the tube between said inwardly turned flanges, a rope extending over said large wheel of sufficient length to have both ends extend to the ground, a seat support in connection with one end of the rope, a seat supported by said support, a loop in connection with said seat support above the seat, and a bracket in connection with the seat support above the seat. 15

PHILIP A. STEPHENS.
